UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,152,138.

Specification of Letters Patent. Patented Aug. 31, 1915.

Application filed January 21, 1910. Serial No. 539,258.

To all whom it may concern:

Be it known that I, ARTHUR J. BAZELEY, of Cleveland, county of Cuyahoga, State of Ohio, have invented a new and useful Improvement in Car-Couplings, of which the following is a full, clear, and exact description, reference being had to the accompanying drawings, forming part of this specification, in which—

Figure 1 is a sectional plan view of a coupler constructed in accordance with my invention, showing the parts in locked position; Fig. 2 is a sectional side elevation of the same; Fig. 3 is a perspective view of the knuckle showing the bottom face of its tail; Figs. 4, 5 and 6 are vertical longitudinal sections; Fig. 4 showing the parts in lock-to-lock position, Fig. 5 in lock-set position and Fig. 6 in the knuckle-thrown position; Figs. 7, 8 and 9 are transverse sections looking toward the rear; Fig. 7 showing the parts in lock-to-lock position, Fig. 8 in lock-set position, and Fig. 9 with the knuckle in open position; Fig. 10 is a view similar to Fig. 2, showing the parts in lock-set position; Fig. 11 is a side elevation; Figs. 12 and 13 are elevations of the locking block on a larger scale; Fig. 14 is a perspective view showing the lock lift lever and its shaft; Figs. 15 and 16 are respectively, an elevation and a plan of the operating lever; Fig. 17 is a view showing a modified form of shaft and operating mechanism; and Fig. 18 shows a modified form of connections between the operating lever and the lock lift lever.

My invention relates to the class of car couplers, and is designed to relieve the strain on the pivot pin and add strength. It is also designed to provide an improved locking mechanism and lock-operating mechanism.

In the drawings, referring to the form of Figs. 1 to 16, inclusive, 2 represents the head of the coupler and 3 the knuckle.

The knuckle tail 4 is provided with an angular bearing surface 5 for the locking block 6. This bearing surface extends at an angle to the line of draft and fits the correspondingly inclined face of the locking block. The tail is also provided upon

its opposite side with an angular projection 7, which enters a correspondingly shaped recess 8, in the wall of the coupler head, and has a forwardly inclined face 9, 55 fitting the correspondingly inclined face of the coupler head recess, so as to draw against it, when in closed position. These engaging parts are preferably inclined at an angle of 45° to the line of draft. The 60 faces 9 and 5 diverge rearwardly. The tail is also preferably provided with a horn 10, which projects through a side hole in the coupler head. The faces 5 and 9 preferably extend vertically. The pivot pin hole in 65 the hub of the knuckle is preferably provided with sufficient clearance to give freedom for the knuckle in its opening and closing movements, and to allow the strain of draft to come primarily on the tail faces 70 5 and 9, and relieve the strain on the pin. The widening of the bearing faces of the tail toward the rear end adds strength thereto, increasing the bearing surface.

The locking block 6 is shown in Figs. 12 75 and 13. It is of the single vertical pin type with its front portion cut away, as shown at 11, to allow passage of the knuckle tail when lifted. This cutting away leaves a shoulder 12, which rests upon the elevated 80 top face of the horn portion 10, when the knuckle is open. The upper portion of the locking block is also provided with a recess 13, preferably having a vertically inclined face 13', which bears on a vertically inclined face on the knuckle tail. This gives a rearward wedging action on the tail to cause the face 9 to engage the recess in the head. This gives an initial tight fit for these parts. This block 6 has a projection 90 11, which overhangs the lock lift lever shaft to prevent dropping down of the lock beyond its normal position.

The lower portion of the locking block is provided with a cam recess 15, within which 95 the lug 16 of the lock lift lever 17 operates. This lock lift lever is loosely mounted on a stationary axle 18, which is driven horizontally inward through a hole in the lower side portion of the coupler, taking the position shown in Figs. 7, 8 and 9. It is held in this position by a locking means, such as

a cotter pin 19, which is driven down through a vertical hole in the floor of the coupler cavity beyond the outer end of the pin when driven home. In this way, the 5 axle can not be accidentally removed without the cotter being voluntarily removed from the inside of the coupler. The lock lift lever 17 is provided with an upwardly extending push portion 20, which engages the curved rear face 21 of the knuckle tail 4, to push the knuckle open after unlocking.

The operating lug 16 of the lift lever performs the functions of lifting the locking block and of co-operating therewith to act 15 as a lock for the lock to prevent creeping thereby, while the lever itself, carrying the lock, acts to throw the knuckle open. The lever 17 being loosely pivoted, any tendency of the locking block to creep upwardly will cause the lower shoulder 23 on the locking block to abut against the angular shoulder of the lug 16 and jam in such a way as to prevent further upward movement of the lock. When, however, a lifting force is applied to the lever 17, there is no jamming and the lug 16 acts upon the upper wall of the recess 15 to lift the lock.

The lock-setting is performed in the following manner: The lug 16 is provided with 30 an angular corner portion for part of its surface, and as the lever 17 is pushed upwardly, its rotation brings the angular corner portion of the lug 16 into engagement with a shoulder 22, forming part of the upper wall of the recess 15, which recess is enlarged forwardly as shown in Figs. 9 and 10. This angular portion of the lug also engages a similar shoulder 23, in the bottom wall of the recess, thus giving the lock to the 40 lock feature.

It will be seen that, owing to the angular shape of the lug 16, its coaction with the shoulders on the top and bottom walls of the lock recess prevents accidental upward movement of the lock and also causes the engagement which gives the lock set. When the parts are in the normal locked position, any accidental upward movement of the locking block will cause a toggle-like action 45 between the lower shoulder 23 and the angular shoulder of the lug, since the lug in its rotation will carry the angular portion out away from its pivot, and thus tend to jam the vertical face of the locking block against the wall of the coupler. This same action occurs in the lock-set position when the angular portion engages the upper shoulder 22 after the locking block has been raised to the lock-set position. In one position of rotation of the lever 17, the lock will be held in lock-set position, while further rotation will cause the lug 16 to ride along the inclined face 24, without further lifting of the lock. During this further rotation, the extended

end 20 of the lever 17 will push the knuckle 65 open. During this opening movement, the lock will be held up by the engagement of the lug 16 with the inclined top recess wall until the tail nears the end of its movement, when its rising upper surface will engage 70 and support the lock by engaging the shoulder 12 thereof. The lock-set position is shown in Fig. 5, and the position of the parts with the knuckle open in Fig. 6. When the lifting action is released, the lever 20 will drop from the position into which it has been forced backwardly until the lug 16 strikes the part 15^a on the locking block. The lever is free to take this action under gravity because the lock is at this time suspended on the upper higher face portion 10 of the knuckle tail, thus leaving the lever free to swing under gravity. This is an important feature, because it avoids liability of the lever stopping after a portion of this rearward swing which might lock-set the lock. As the knuckle tail now moves rearwardly, the lock moves down from the upper face 10 of the knuckle tail, the tail swings through the recess in the lock and the locking block drops down to place. It will therefore be seen that the locking lever drops back to its normal relation with the lock before the lock has dropped to its lowest position. The lock and the lock lift lever then 95 both drop down to their final lowermost position after the knuckle tail has passed through the opening in the locking block.

Any desirable form of bottom operating mechanism may be employed for forcing the lock lift lever upwardly. In the form shown, there is a bottom-operating lever 25, which is pivoted between lugs 26, depending below the pivot pin hole, the hub of the lever thus also acting as a pivot pin support in 105 case of breakage. At its bend, the lever is provided with a hole or eye 27, to receive the uncoupling lever 27^a, one hooked end of which is pivotally engaged with a lug 27^b on the coupler head, while the other end 110 may be engaged by the usual lifting chain, secured to a cross rod, not shown. The upwardly curved inner portion of the operating lever abuts against the lower outer end portion of the lever 17, to lift this lock lift 115 lever.

In order to limit the downward movement of the operating lever 25, I preferably provide it with a side projection or lip 28, which, when the parts are assembled, is 120 above an inwardly projecting lip 29, on one of the hinge lugs of the lever.

Instead of pivoting the lock lift lever loosely on an axle, a shaft may be arranged to operate it. Thus, in Fig. 17, I have 125 shown the shaft 18^a as being lengthened, with its outer portion projecting through the side of the coupler head, and having an op-

erating arm 30, which may be connected by a chain 31, to the uncoupling lever or may be otherwise operated. In this case, the intermediate portion of the shaft is secured to the lever 17 by a spline connection 32, and the outer portion of the shaft which is preferably enlarged may be provided with a groove 33, engaged on one side by a cotter or pin extending through a vertical hole in side the coupler. This cotter or pin will prevent endwise movement of the shaft, while allowing its rotation. In this case, the rotation of the shaft will swing the operating lever 17, the action being the same as before. Instead of allowing the operating lever to merely abut against the lock lift lever, I may provide them with a pivotal link connection 34, as shown in Fig. 18.

The advantages of my invention result from relieving the pivot pin from a great part of the strain thereon, without departing from the usual M. C. B. lines. Also from the simple and effective lock and lock-operating mechanism, which provides for locking the lock, lock-lifting, lock-setting, and knuckle-throwing.

Many variations may be made in the form and arrangement of the parts without departing from my invention.

30 I claim:—

1. The combination with a coupler and knuckle, of a lock-lift lever mounted on an axle fixed in the coupler head, and a vertically-movable locking block having an intermediate recess or cut-away portion to allow passage of the knuckle, said locking block having a projecting portion overhanging the lock-lift lever axle to avoid accidental dropping; substantially as described.

40 2. In a coupler, a swinging knuckle, a lock movable bodily in a vertical direction, a lock-lifting lever separate from the lock and mounted on an axle fixed in the coupler head and being adapted by a rotative movement to lift the lock, and a bottom-operating lever arranged to actuate the lift lever, said operating lever having engagement with the coupler arranged to limit its downward swing, substantially as described.

45 3. In a coupler, a swinging knuckle, a vertically-movable lock having a recess with upper and lower shoulders, and a lock-lifting lever pivotally mounted on an axle extending transversely of the coupler head below the knuckle, said lock-lifting lever having an arm arranged when in lockset position to engage the upper shoulder of the lock recess and thereby maintain the lock in lockset position and being also arranged in

50 locked position to engage the lower shoulder of the lock recess to act as a lock-to-the-lock.

4. A knuckle-opening and locksetting piece having a fixed pivot in the lower portion of the coupler cavity, and a lock having

a recess in the lower portion thereof, the said piece being adapted in lowermost position to engage against one portion of the lock in said recess to act as a lock-to-the-lock, and in another position to engage against another portion of the lock in said recess for lock-setting, the said piece being adapted to drop by gravity into lowermost position after knuckle-throwing.

5. A coupler having a swinging knuckle, a vertically-movable lock having below its locking head a recess with upper and lower walls, a lock-lifting and knuckle-throwing lever pivoted below the knuckle tail and swinging in a vertical plane, and a bottom lever pivoted to the underside of the coupler head and adapted to engage and actuate the first-named lever, said first-named lever, when the parts are in lowermost position, co-acting with the lower wall of the recess in said lock to act as a lock-to-the-lock, and when the parts have been lifted to lockset position co-acting with the upper wall of the recess to support the lock in lockset position, said lever being adapted, on its further actuation by the bottom lever, to co-act with the knuckle tail and throw it to open position.

6. A coupler having a swinging knuckle, a vertically movable lock having below its locking head a recess with upper and lower walls, and a knuckle-throwing lever pivoted beneath said knuckle to swing in a vertical plane, said lever having a knuckle-engaging arm and a lock-engaging arm projecting laterally from the knuckle-engaging arm, said lock engaging arm projecting into the recess in the lock and being adapted to coact with the lower wall when the parts are in lowermost position, to prevent the lock from creeping, and also being adapted to coact with the upper wall when the lock has been lifted to maintain the lock in lockset position.

7. A coupler having a swinging knuckle, a vertically movable lock, and a lock-lifting and knuckle-throwing lever pivoted in the coupler cavity below the knuckle tail to a transversely-extending axle and being adapted to swing in a vertical plane, said lever having in fixed relation thereto two arms on the same side of its pivot, one of said arms being adapted to engage and throw the knuckle and another arm extending laterally from the first-named arm and being adapted to engage and lift said lock and support it in lockset position.

8. A coupler having a swinging knuckle, a vertically-movable lock, a knuckle-throwing lever mounted on a fixed pivot in the lower part of the coupler cavity to swing in a vertical plane and being adapted to engage said knuckle and said lock, and a second lever pivoted to the underside of the coupler

head to swing in a vertical plane and being adapted to engage the first-named lever, the first-named lever engaging the lock when it is in lowermost position to prevent it from creeping and also engaging the lock when it has been lifted to support it in lockset position.

In testimony whereof, I have hereunto set my hand.

ARTHUR J. BAZELEY.
